Attorney

UNITED STATES PATENT OFFICE.

SAMUEL S. DRAKE, OF BOISE, IDAHO, ASSIGNOR OF ONE-HALF TO RICHARD H. JOHNSON,
OF BOISE, IDAHO.

FISHING-TOOL.

1,290,127.

Specification of Letters Patent:

Patented Jan. 7, 1919.

Application filed May 9, 1918. Serial No. 233,563.

To all whom it may concern:

Be it known that I, SAMUEL S. DRAKE, a citizen of the United States, residing at Boise, in the county of Ada and State of Idaho, have invented certain new and useful Improvements in Fishing-Tools, of which the following is a specification.

My invention relates to improvements in fishing devices and more particularly to devices used for removing broken or lost tools from oil, gas or water wells.

In drilling wells it sometimes happens that the drilling string breaks or becomes disconnected somewhere between the bit head and upper end of the rope, and when this occurs it is necessary to remove the tools or parts left in the well before proceeding with the drilling.

Various devices have been proposed for removing the lost parts from the well and these devices usually comprise special tools, which are lowered in the well, and the construction of which is particularly adapted for grasping or cutting one part of the drilling string only. In other words, if the joint at one point in the string becomes disconnected, then one form of fishing tool is used for grasping the part of the joint, which remains in the well, while if the string breaks at the jars, for instance, then another form of fishing tool must be used. Therefore, it has been the custom heretofore to use tools particularly designed for catching the string at one point only, and as the string is liable to break or disconnect at various places, a multiplicity of fishing tools must be kept on hand, in order to recover the lost parts of the string.

The present invention was designed with a view of eliminating the necessity of employing tools, which would grasp the well string at one point only, and with the idea of avoiding the expense incident to the purchase of said tools.

The primary object of my invention is to provide a single tool having a set of detachable parts, which are interchangeable, so that a common tool can be used with parts particularly designed to engage the string at various points.

Another object of my invention is to provide such a tool with means for adapting the same to wells of different diameters.

A further object of the invention is to furnish a tool having interchangeable

grasping mechanism, into contact with which the lost parts of the spring are guided by means of interchangeable hooks, carried by the tool.

With the foregoing objects outlined and with other objects in view, the invention consists in the novel features hereinafter described, in connection with the accompanying drawing, and the said invention is fully disclosed in the following description and claims.

Referring to the drawing:

Figure 1 is a perspective view of my improved tool showing an eccentric attached thereto, and especially designed for engaging a broken rope.

Fig. 2 is a bottom plan view of the same.

Fig. 3 is a side view of a different form of rope gripping eccentric.

Fig. 4 is a perspective view of an eccentric to be used with the tool, when it is desired to grasp a bit, sinker rod, or a threaded portion of any of the drilling tool parts.

Fig. 5 shows a latch, which is used with the tool when it is desired to grasp or catch one of the jars.

Fig. 6 is a perspective view of a rope-cutting attachment.

Fig. 7 is a perspective view of a modified form of tool having a flat shank, which is especially useful in drilling wells of small diameter, as the stock does not have to be so heavy.

In Figs. 1 to 6 of the drawing, 1 designates the shank of my improved fishing tool, which is provided at its upper end with a screw-threaded part 2 adapted to be screwed into a threaded socket (not shown) carried by a cable that is lowered into the well. The shank is provided at its lower end with arms 3 and 4, which extend at right angles to the shank, and the arm 4 has a post 5 extending substantially parallel to the arm 3. A hook 6, which may be made in different lengths and of various curvatures to accommodate wells of various diameters, is secured to the arm 3 by a mortise and tenon joint 7 and a removable pin 8. Different parts or attachments, hereinafter described, are adapted to be secured to the post 5 for engaging various portions of the well string.

In use, assuming that the rope or cable of the drilling string has broken, either one of the rope eccentrics 9 (shown in Figs. 1 to 3), are attached to the post 5, and se-

cured by means of any suitable fastening means, such as a cotter pin 10. The eccentric shown in Figs. 1 and 2 has an extending tail 11 provided on one side with teeth 12, while the eccentric shown in Fig. 3 is provided on its periphery with graduated teeth 13. When the tool provided with either of the rope eccentrics is lowered into the well, the tool is turned toward the right 10 until the string cable is guided by the hook 6 into contact with the shank 1. Then if the tool is lifted, the rope will swing the eccentric 9 about its pivot or post 5 until the teeth firmly bite into the rope. When this 15 occurs, the fishing tool may be raised and will carry the lost parts with it.

Should the string break at the bit, sinker rods, or joints, then the eccentric 14 shown in Fig. 4 is used with the tool. This eccentric 20 is provided with peripheral teeth 15, which extend across the circumference of the eccentric, and are adapted when the tool is lowered to engage the broken part and grasp the same when the fishing tool rope is 25 elevated.

The attachment 16 shown in Fig. 5 is used when the string breaks at the jars, and in use it is placed on the post 5 and its free end 17 rests on the upper surface of the 30 arm 3. When the tool is lowered, the arm is raised by contacting with the upper end of the lost jar and remains in this position until the tool is lowered sufficiently to permit the latch 16 to fall through the slot of 35 the jar. Then as the tool is raised the latch 16 will engage the upper wall of the jar slot and raise the jar and its connected parts.

In Fig. 6, I have shown a rope-cutting attachment 18, which may be attached to the 40 post 5, when it is desired to cut the drilling string rope near the drilling tools, so that the upper end of the tools may be grasped by the eccentric 14 in a manner similar to that described in connection with Figs. 1, 45 2 and 3. The part 18 has a curved cutting edge 19, which, when the tool has engaged the drilling rope at the proper point, will cut through said rope.

In the modified form of tool, shown in 50 Fig. 7, I have provided a flat shank 1^a having a threaded portion 2^a; an arm 3^a for carrying the hook 6^a; and a post 5^a, which extends parallel to the arm 3^a. All of the parts shown in Figs. 1 to 6 inclusive, are attachable to this form of tool in a manner similar to that described in connection with Figs. 1 and 2, and need not be repeated. As before stated, however, the tool shown in Fig. 7 is particularly adaptable for use in 55 fishing for lost tools in wells of small diameter.

In practical use my fishing tool is attached to the well drilling cable at the end of the string of tools which are added to 60 secure the weight. The cable is first twisted

to the left several turns just above the place where the lost tools are situated, and so held with wrenches or tongs or twistees until they reach the place where you wish to take hold, and then released. When the twist 70 comes out the hook will naturally go behind the lost tool and the curve in the hook will throw the fishing tool to its proper place. The upward pull causes the eccentric to revolve until it has the proper hold. The 75 stronger the upward pull, the tighter it holds. It can be released at any time by lowering or jarring down with the fishing string and twisting back until released and so held until raised above the lost tool. This 80 is important because in some few instances it may happen that the lost tools are so tightly wedged that sufficient power on the surface is not available to hoist them.

While I have shown and described the 85 preferred embodiments of my invention, it is nevertheless to be understood that various forms, modifications and arrangements of the parts may be made without departing from the spirit of the invention or sacrificing 90 any of its advantages.

What I claim and desire to secure by Letters Patent is:

1. A fishing tool comprising a shank provided at its upper end with means for attaching the same to the extreme lower end of a hoisting cable, a hook carried by the shank and extending at an angle thereto for guiding a well string into contact with the shank when said shank is turned, a post carried by the shank, and a member pivotally mounted on said post and co-operating with said hook for automatically operating on the well string when said shank is raised, said member being connected only to said post and being automatically operative independent of any other part of the tool. 95

2. A fishing tool comprising a shank provided at its upper end with means for attaching the same to the extreme lower end of a hoisting cable, a hook carried by the shank and extending at an angle thereto for guiding a well string into contact with the shank when said shank is turned, a post carried by the shank, and a member pivotally and detachably mounted on said post and co-operating with said hook for automatically operating on the well string when said shank is raised, said member being connected only to said post and being automatically operative independent of any other part of the tool. 110

3. A fishing tool comprising a shank provided at its upper end with means for attaching the same to a hoisting cable, a hook carried by the shank and extending at an angle thereto for guiding a well string into contact with the shank, a post carried by the shank, and an eccentric pivotally mounted on said post and automatically co-operat- 125

ing with the hook for grasping the well string when the hoisting cable is raised, said eccentric being connected only to said post and being operative independent of any other part of the tool.

- 5 4. A fishing tool comprising a shank provided at its upper end with means for attaching the same to a hoisting cable, a hook carried by the shank and extending at an 10 angle thereto, a post extending at an angle to the shank and parallel to a portion of the hook, an eccentric pivotally mounted on said post and coöperating with said hook for automatically grasping a well string when 15 the hoisting cable is raised, said eccentric being connected only to said post and being automatically operative independent of any other part of the tool, and means for detachably securing the eccentric on the post.
- 20 5. A fishing tool comprising a shank provided at its upper end with a screw threaded member for attaching the same to a hoisting cable, arms carried by the lower end of said shank and extending at right angles to the

shank and to each other, a hook detachably 25 connected to one of said arms for guiding a well string into contact with said shank, a post carried by the other arm and extending parallel to the first arm, and an eccentric pivotally and detachably mounted on said 30 post and adapted to automatically grasp the well string when the tool is raised, said eccentric being connected only to said post and being operative independent of any other part of the tool.

35 6. A fishing tool comprising a shank provided with a hook for guiding a well string into contact with the shank, and a pivotally mounted eccentric adapted to automatically clamp the well string between the hook and 40 eccentric when the tool is raised.

In testimony whereof I affix my signature in the presence of two witnesses.
